UNITED STATES PATENT OFFICE.

BAILEY CLAYTON CAUDRY, OF COFFEYVILLE, KANSAS.

DEVICE FOR REMOVING OR ELEVATING LAMP-CHIMNEYS.

SPECIFICATION forming part of Letters Patent No. 678,939, dated July 23, 1901.

Application filed December 7, 1900. Serial No. 39,066. (No model.)

To all whom it may concern:

Be it known that I, BAILEY CLAYTON CAUDRY, a citizen of the United States, residing at Coffeyville, in the county of Montgomery and State of Kansas, have invented certain new and useful Improvements in Devices for Removing or Elevating Lamp-Chimneys, of which the following is a specification.

My present invention pertains to improvements in devices for removing or elevating lamp-chimneys, the construction and advantages of which will be hereinafter set forth, reference being had to the annexed drawings, wherein—

15 Figure 1 is a perspective view of a lamp-chimney, showing my invention applied thereto; Fig. 2, a perspective view of a portion of the chimney, illustrating another application of my invention; Fig. 3, a face view of one 20 of the non-conducting disks or buttons; Fig. 3^a, a sectional view thereof; and Fig. 4, a perspective view of a modified form of disk or button, the parts being shown as separated.

The object of my invention is to present a 25 simple and efficient means for permitting the ready removal of a hot lamp-chimney or the elevation of the same from the burner to clear the wick or parts from any obstruction.

The invention in its breadth comprises the 30 use of disks or buttons of some non-heat-conducting material, with means for attaching them oppositely disposed to the chimney, so as to afford a handhold by which the chimney may be removed or elevated.

35 Referring more particularly to Fig. 1, A denotes a chimney the lower edge of which is provided with notches or recesses B, diametrically placed for the reception or passage of the retaining-arms C, which are attached to 40 the button or disk D of non-conducting material. In practice the button or disk will preferably be formed of asbestos or similar substance which will not be affected by the heat transmitted to it through the chimney 45 or conducted to it by the spring retaining-arms C.

In Fig. 2 the disks or buttons are shown as being placed or secured to the upper end or top of the chimney, in which position it is not, 50 of course, necessary to notch the chimney, the notching shown in Fig. 1 being simply to permit the chimney to come to rest fairly upon

the chimney-support, thus preventing any draft up through the chimney which would interfere with the proper burning of the flame. 55

In Figs. 3 and 3^a the spring-arms are shown as formed of a single piece of wire, the main body portion of which is embedded in the material of which the button or non-conducting disk is formed. 60

In Fig. 4 the disk is shown as provided with a groove or channel in its periphery, the body portion C' being sprung into said groove or channel, thus uniting the two parts.

It is manifest that many forms of disk and 65 attaching means may be employed, and the invention is not, therefore, to be restricted to the particular forms shown.

From the foregoing description and from the drawings it will be seen that the buttons 70 or disks may be readily applied to any form of chimney and that they will afford a proper hold for the purpose of elevating or removing the chimney from the lamp, and this without fear or danger of burning the fingers. 75 The disks or buttons being formed of non-conducting material may be left in place.

It will be seen that the disks in and of themselves form a salable article and may be marketed separate from and independent of 80 the chimney.

As will be noted upon reference to Fig. 4, the disk or button may have printed, embossed, or otherwise formed upon it the name of the manufacturer or suitable advertising 85 matter.

Having thus described my invention, what I claim is—

1. In combination with a lamp-chimney, a pair of independent non-heat-conducting finger-holds, detachably secured thereto. 90

2. In combination with a lamp-chimney having notches or recesses formed in its lower edge, a pair of finger-holds, and means for securing said holds to the chimney, said means being seated in the notches or recesses, substantially as described. 95

3. A finger-hold for lamp-chimneys, comprising a non-heat-conducting disk or button provided with means for securing it to a lamp-chimney. 100

4. A finger-hold for lamp-chimneys, consisting of a non-heat-conducting disk or button, and spring retaining-arms secured to said disk

or button adapted to grasp the edge of the chimney.

5. A finger-hold for lamp-chimneys, comprising a disk or button of non-conducting material having a groove or channel formed in its periphery, and a wire loop seated within said groove or channel and having spring retaining arms or fingers formed at its ends.

In testimony whereof I have signed my name to this specification in the presence of 10 two subscribing witnesses.

BAILEY CLAYTON CAUDRY.
